UNITED STATES PATENT OFFICE.

HAROLD ROWNTREE, OF CHICAGO, ILLINOIS, ASSIGNOR TO NATIONAL PNEUMATIC COMPANY, A CORPORATION OF WEST VIRGINIA.

DOOR-OPERATING MECHANISM.

1,168,334.

Specification of Letters Patent. Patented Jan. 18, 1916.

Application filed May 5, 1910. Serial No. 559,491.

To all whom it may concern:

Be it known that I, HAROLD ROWNTREE, a citizen of the United States, residing at Chicago, county of Cook, State of Illinois, have made a certain new and useful Invention 5 in Door-Operating Mechanism, of which the following is a specification.

This invention relates to mechanism for operating the doors of street cars.

10 The object of the invention is to provide a car or other door operating mechanism which is simple in structure, economical to manufacture, and efficient in operation.

15 A further object is to provide means which are simple and efficient for locking the apparatus in position to hold the doors open or closed.

20 A further object is to provide means in a manually operated apparatus of the character referred to for retarding the final movements of the door.

25 Other objects of the invention will appear more fully hereinafter.

The invention consists substantially in the 30 construction, combination, location and relative arrangement of parts, all as will be more fully hereinafter set forth, as shown in the accompanying drawings, and finally pointed out in the appended claims.

35 Referring to the accompanying drawings, and to the various views and reference signs appearing thereon,—Figure 1 is a plan view, parts in horizontal section of a portion of the end of a car showing door operating mechanism having a construction, arrangement and relation embodying the principles of my invention. Fig. 2 is a broken view in vertical section on the line 2, 2, Fig. 1, showing the guide roller and guides for the inner 40 folding door section. Fig. 3 is a broken view in top plan, parts in horizontal section, showing a cushioning arrangement embodying my invention. Fig. 4 is a broken view in elevation.

45 In my Patent No. 937,870, dated Oct. 26, 1909, is shown, described and claimed, a construction of twin folding doors, the folding movements of the door sections being effected by means of intermeshed gears. In the 50 use of apparatus embodying the construction

of said patent, however, different patterns and castings are required for each width of door. It is among the special purposes of my present invention to provide door operating means which are simple and efficient, 55 and which are of standard uniform construction whatever may be the differences in width of the doors.

In carrying out my invention I provide doors made in sections or panels hinged together and designed to fold upon each other to open the doorway and to straighten out into substantially the same plane when closed, the folding movement of the one section or panel upon the other in opening being effected by means of a guiding roller or device connected to the folding section or panel of the door and operating in a guiding way or track.

55 In the drawings, reference letters A and B designate respectively the outer and inner panels or sections of each door. Each outer section A is secured at its outer edge to a vertical rock shaft C, to rock or swing therewith. Each inner section or panel B, is 60 hinged at its outer edge to the inner edge of its coöperating door section A, as indicated at D. Secured to each door section B, is a bracket or shoe E, carrying a guiding device, in this instance a roller F, arranged to be 65 received and to operate in a way or track, indicated at G, formed in or connected to the under surface of the ledge or frame immediately over the doorway. This guide way or track may be of any suitable construction 70 and arrangement. I have shown a simple embodiment wherein angle plates H, J, are 75 provided and separated sufficiently from each other to afford a trackway therebetween. The plate H, extends practically all 80 the way across the doorway while the plates J, are short and terminate with their proximate ends considerably separated at the center of the doorway. A block or shoe K, is 85 attached to the framing beam above the 90 doorway at the center of the doorway, and is provided with somewhat rounding or curved side edges.

95 The operation of this part of my invention is simple and is as follows:—Suppose 100

the doors occupy their closed positions, as shown in Fig. 1, and it is desired to move them to their open position. The shafts C, are rotated thereby swinging the sections 5 or panels A about the axes of said shafts. At the commencement of the rocking or swinging movement of the door sections A, the hinge joints between the door sections A, and B, are bent at D, thereby slightly 10 rocking the door sections B about the bearing points thereof against the shoe K, as a fulcrum. This movement causes the rollers F, to move outwardly a sufficient distance to enable them to enter the guide ways or 15 tracks G. The continued swinging movement of the door sections A, toward open position, causes the guide rollers F to be drawn through the guideways or tracks G, thereby causing the door panels or sections 20 B, to fold back against the panels or sections A, into the complete open positions thereof. By rotating shafts C, in the opposite direction the panels or sections A, are rocked toward their closed position, thereby pushing 25 the guide rollers F along the guideways G, toward the inner ends thereof. The extreme inner edges of the sections B, are eventually brought into engagement with the rounded or curved sides of the shoe K, 30 and thereby guided firmly and securely into their completely closed positions against the stop or head L, as the joints between the panels A, B, straighten out, the extreme inner edges of the panels B being forced 35 into the space between the shoe K, and the head L.

It will be observed that I am enabled to employ straight instead of curved guideways 40 which have usually been employed and which are a source of trouble by reason of the guides becoming wedged therein in case of the slightest inaccuracy in forming the curve on the exact radius of curvature. By employing straight guideways, and offsetting from the door sections the guides which 45 co-operate therewith, I am enabled to produce an arrangement which is exceedingly simple and economical to make and install, and wherein an easy action of the door section or panel movements is secured without 50 binding or wedging.

The movements of the door sections or 55 panels to open or closed positions may be effected in many different ways, by power or manually operated devices, and from any convenient point. In the particular arrangement shown, to which, however, my invention in its broadest scope, as defined in the claims, is not to be limited or restricted, I provide manually operated devices 60 for moving the door sections or panels, and where the doors are applied as side doors for street or other car platforms, as in the case illustrating my invention as

shown in the drawings, I propose, in accordance with the principles of my invention to locate the point of control of the doors on one side of the platform in such relation to the car body and platform as to define separate entrance and exit passages to and from the interior of the car body across the platform from and to the side door way. To this end I employ a stand M, at the point referred to, within which is arranged a vertical operating shaft N, having an operating 70 handle O, at its upper end by which said shaft may be rotatively actuated. The operating shaft N, extends below the floor P, of the platform, and at its lower end is suitably connected to the rock shafts C, in such 75 manner that when the operating shaft N, is rocked, a corresponding rocking movement is imparted to the shafts C, and, consequently, also to the door panels or sections 80 A, and B, as above explained. A simple 85 and efficient arrangement is shown wherein a crank arm 10, is mounted on shaft N, said crank arm having a broadened free end, as shown. To the two corners of the broadened free end of this crank arm are pivotally 90 connected, as at 11, 12, operating rods 13, 14. In order to prevent interference in the proper operation of these devices, I prefer to attach one of these operating rods 13, to the upper side of crank arm 10, and the 95 other 14 to the lower or under side thereof, as most clearly shown in Fig. 4. I also suitably curve or bend one of the rods, as indicated at 15, so that said rod will not be prevented by shaft N, from properly operating 100 to the required extent to perform its full function. The other ends of the rods 13, 14, are pivotally connected to crank arms 16, respectively connected to the door section or panel operating shafts C, and respectively 105 extending in opposite directions, so that when operating shaft N, is rotated the door section carrying shafts C are simultaneously rotated in opposite directions with respect to each other.

In Fig. 4 I have shown a step cover in the form of a panel arranged to form a riser 17, for the car step 18 when the doors are open, but designed to be shifted outwardly, as indicated in dotted lines, to form a step 110 115 cover when the doors are closed, the shifting of the step cover being accomplished coincidently with the door movements by means of a rod 22, connected to the panel, as at 21, and to the door operating rod 14, as at 120 23, the riser panel being pivotally suspended from links 19, pivoted to the side brackets 20 of the step.

In the operation of doors and particularly in the case of car doors, it is desirable to lock 125 the doors in the limits of their movements to open or closed positions. This result is accomplished in the structure embodying

my invention as illustrated in the drawings, by so arranging the parts that when the doors are in their fully closed positions, the points 11, 12, of pivotal connection of the 5 rods 13, 14, to the crank arm 10, are respectively, in substantially a dead center line with the axis of operating shaft N, and the points of pivotal connection of said rods with the crank arms 16, on the door operating 10 shafts C, thereby locking the doors closed.

It is desirable to cushion the final movement of the doors to open or closed positions. Where power operated means are 15 employed for this purpose the cushioning may be easily and readily accomplished, but in the case of manually operated devices the difficulty becomes more serious, as the manual operation of the doors requires the expenditure 20 of considerable effort on the part of the operator, and any retarding or cushioning device that might be employed would require additional physical effort. Moreover, if the cushioning or retarding action 25 is only slight a strong vigorous operator might cause the doors to slam notwithstanding the use of the cushioning or retarding means, and if the cushioning or retarding action is strong then a less vigorous operator 30 might fail to completely open or close the door, thereby inviting danger of accident. In accordance with the principles of my invention, I propose to obviate these difficulties, and to provide means for efficiently retarding 35 or cushioning the final movements of the doors and, in case of manual operation without imposing too great an additional strain on the operator. A simple arrangement, as illustrative of the principles involved is shown, wherein the crank arm 40 10, is loosely mounted on shaft N, and is provided near its free end with a slot curved on an arc struck from the axis of shaft N, as a center, in which slot operates the bent 45 end 29, of a crank arm 30, secured to and rocking with the shaft N. Also connected to the arm 10, is one end of a link 31, the other end thereof being connected to the rod 32, of a piston 33, operating in a cylinder 34. The piston 33, is provided with a 50 hole or opening 35, therethrough which is closed when the piston moves in one direction by a flap valve 36, loosely carried by a stud 37, and adjusted by a set screw 38. When 55 the piston moves in the other direction the flap valve 36, uncovers the opening 35. A spring 39, is interposed between the piston 33, and one end of the cylinder 34.

The operation of this feature of my invention is as follows:

When the operating handle O, is turned, thereby turning the shaft N, the end 29 of the crank arm 30, moves through the slot 27 in arm 10, without doing any work until the

end of slot 27 is reached whereupon the arm 65 10, is thereafter rocked with arm 30. This movement, starting with the parts occupying the positions thereof indicated in Fig. 3, that is, in their normal positions with the doors closed, causes the piston 33 to be moved 70 in cylinder 34, against the action of spring 39, until the arm 30 has moved through a distance somewhat greater than ninety degrees, or until the link 31, has passed its dead center point. Thereafter the physical 75 effort of the operator in completing the door movements to open position, is aided by the tension of spring 39, which now tends to complete the swing of arm 10, thereby very 80 materially relieving the operator in accomplishing the work.

When the operating handle has moved to its extreme position the crank arm 10, will lack somewhat of being in its extreme position owing to the lost motion in the slot in 85 the crank arm, and, therefore, when the operating handle O, has been moved to its extreme position the door will lack somewhat of being in its completely opened or closed position. The spring 39, acting 90 against the air in the cylinder 34, which is compelled to escape through the opening 35, which is nearly closed by the flap valve 36, will gradually move the crank arm 10 into its complete dead center position, thereby 95 completing the movement of the door into its final open or closed position. No matter, therefore, how rapidly or violently the operator may move his crank arm to its final position, he cannot cause the door to 100 slam as the final movement of the door will be accomplished by the spring acting against the dash pot, the lost motion in the slot of the crank arm 10, rendering it impossible 105 for the operator by main strength to force the door to its completely closed or open position.

Thus it will be seen that the spring 39 is being placed in compression by the manual rotation of shaft N, through the power applied to handle O, by reason of the engagement of the end 29 of arm 30, with the end wall of the slot in crank plate 10, which causes said crank plate to move with the shaft N. This continues until the link 31, 115 passes its dead center. Thereafter the tension of the spring becomes effective to continue the rotation of the crank plate 10 independently of the shaft N and handle O, to the extent permitted by the length of the 120 slot 27. This movement, however, is retarded by the restricted exhaust of the air from one side of the piston 33, to the other through the restricted passage 35. This restriction effects the cushioning action and 125 such action takes place whether the final rocking movement of the crank plate 10 is accomplished wholly by the spring or by

power applied to the handle O. The final limit of movement of the piston 33, in cylinder 34 serves to arrest the movement of the crank plate whether such movement is accomplished through the spring or through the handle O, and whether said crank plate is moved to one or the other limits of its throw.

It will also be seen that the same operation takes place when the handle O, is operated in the reverse direction to close the doors. It will also be seen that the spring 39, holds the crank 10 in the extreme limits of its movements, with the door operating rods 13, 14, in their dead center or locked positions, whereby the danger is avoided of the door locking means being jarred or jolted loose in the case of street or railway car operation, or other rough usage.

20 In the foregoing description I have referred to the arrangement of the doors only on one side of the car platform, and to the operation of the same from a point embodying the pay-within fare prepayment principle as applied to street cars. It is obvious that my invention is not to be limited or restricted in this respect. In Fig. 1 I have shown both sides of the platform equipped with folding doors, guided and operating as above described. In the case of street cars, however, it may be desirable to employ one side of the rear platform of the car for both ingress and egress of passengers, while the doorways at the other side of said platform remain closed. Or it may be desired to similarly equip each end of the car so that the rear end may be employed both for ingress and egress of passengers, while the front or motorman's end 40 may be employed only for the egress of passengers and either end may be a motorman's end. To enable this arrangement to be employed I similarly equip both sides of the platform at one or both ends of the car, 45 and arrange the control of the doors on one side of the platform in accordance with the pay-within principle, as above explained, while the doors on the other side of the platform are arranged to be controlled from a point convenient to the motorman's controller S, as indicated at R, the arrangement construction and operation being otherwise the same as above described.

While I have shown and described a retarding device for the doors, and while such a feature is desirable, it is not absolutely essential, and may be omitted, as indicated in Fig. 1 in the arrangement operated by the motorman. In this case a spring 45, may be employed to retain the operating crank in the limits of its movements.

I do not claim herein the step or cover, or the combination thereof with the door, nor the combined operating mechanism for the

door and step or step cover, as the same 65 forms the subject matter of another application divided herefrom.

Having now set forth the objects and purposes of my invention, and various arrangements embodying the principles thereof, 70 what I claim as new and useful, and of my own invention, and desire to secure by Letters Patent, is,—

1. The combination with folding door panels, and manually operated devices for 75 moving the same, of means rendered operative by a portion only of the movement of the manually operated devices for independently retarding the final movements of the panels to open or closed position. 80

2. The combination of a door and means for operating the same, including a rock shaft, a crank arm thereon, connections between the crank arm and door, and lost motion connection between the shaft and crank 85 arm.

3. The combination of a door and means for operating the same including a rock shaft, a crank arm thereon, connections between the crank arm and door, lost motion 90 connections between the shaft and crank arm, and means for retarding the crank arm as it approaches the limits of its movements. 95

4. The combination with a door composed of sections respectively arranged on opposite sides of the doorway, of an operating mechanism therefor including an operating shaft, a crank arm thereon, a connecting rod intermediate said crank arm and each of said door sections whereby both connecting 100 rods are simultaneously operated, and means whereby said rods are each in dead center relation with respect to the crank arm when the doors are in closed position. 105

5. The combination with a door composed 105 of sections respectively arranged on opposite sides of the doorway, of an operating mechanism therefor including an operating shaft, a crank arm thereon, a connecting rod intermediate said crank arm and each of said 110 door sections whereby both connecting rods are simultaneously operated and means whereby said rods are each in dead center relation with respect to the crank arm when the doors are in both open and closed position. 115

6. The combination with a door composed of sections respectively arranged on opposite sides of the doorway, an operating mechanism therefor including an operating shaft, a crank arm thereon, connecting rods connected to said crank arm respectively above and below the same, and also respectively connected to said door sections for operating the latter simultaneously, one of said rods having an offset bend therein, and means for rocking said shaft. 120

7. The combination of a door, and means

- for operating the same, including an operating shaft, a crank arm thereon, lost motion connections between the shaft and crank arm, and connections between the crank arm and door, said connections adapted to be brought into dead center relation when the door is in the limit of its movement.
8. The combination of a door, a vertical rock shaft carrying said door, an operating shaft having a crank arm and lost motion connections between the crank arm and the rock shaft.
9. The combination of a door, a vertical rock shaft carrying said door, an operating shaft having a crank arm, lost motion connections between the crank arm and the rock shaft, and means for retarding the final movement of the crank arm toward the limits of its movement.
10. The combination of a door composed of folding panels hinged together, a rock shaft carrying one of said panels, an operating shaft for said rock shaft, connections between said shafts, and means for retarding the final movements thereof.
11. The combination of a pair of doors, respectively arranged at opposite sides of the doorway controlled by said doors and each composed of panels or sections hinged together, a vertical rock shaft carrying the outermost panel or section of each door, and forming a vertical hinge axis therefor at its outer edge, an operating shaft having connection with both rock shafts for rocking them, a fixed shoe arranged to be engaged by the inner edges of the inner panel of each door as the door approaches its closed position, a guide channel located over each door on opposite sides of said shoe and extending in a straight line from said shoe to the other side of the doorway, and means connected to the upper end of the inner door panel of each door for engagement with its associate guide channel, said shoe operating to cause said channel engaging means to enter said channel.
12. The combination of a doorway and a pair of doors therefor, each composed of panels hinged together, vertical rock shafts respectively arranged at opposite sides of the doorway, and each carrying a panel of its adjacent door and forming a vertical hinge axis therefor, a fixed guideway arranged over the doorway and having one wall thereof omitted at midwidth point of the doorway, means carried by another of the panels of each door at the upper free edge thereof, and arranged to engage and operate in said guideway, means to engage the forward edge of the last mentioned panels of both doors as they leave and approach closed position to cause said guideway engaging means to enter and to be withdrawn from said guideway, an operating shaft, a control handle therefor, a crank arm 65 carried by said operating shaft, a crank arm on each rock shaft, and connections between said crank arms.
13. The combination of a door composed of panels or sections hinged together, a vertical rock shaft carrying one of said panels and forming a vertical hinge axis therefor, a fixed guideway, means carried by another of said door panels at the free edge thereof and arranged to operate in said guideway, 70 an operating shaft arranged to divide the space adjacent the doorway into separate passages, a control handle for said operating shaft, a crank arm also carried by said operating shaft, a crank arm on the rock shaft, 75 connections between said crank arms, and means for cushioning the final movements of the door panel operating mechanism.
14. The combination of a door composed of panels or sections hinged together, a vertical rock shaft, carrying one of said panels and forming a vertical hinge axis therefor, a fixed guideway, means carried by another of the door panels at the free edge thereof and arranged to operate in said guideway, 80 an operating shaft having a crank arm and a control handle, a crank arm on the vertical rock shaft, connections between said crank arms, and means normally operating on said operating shaft to hold the same in 85 the limits of its rocking movements to maintain the door panels in their open or closed positions.
15. The combination of a door composed of panels or sections hinged together, a vertical rock shaft carrying one of said panels and forming a vertical hinge axis therefor, said shaft having a crank arm, a fixed guideway, means carried by the free edge of another of said door panels for engagement 90 with said guideway, an operating shaft having an operating handle and a crank arm, connections between said crank arms, and yielding devices normally operating to hold said crank arms in position to maintain said 95 connections in dead center relation at each limit of movement thereof.
16. The combination of a doorway, a pair of doors therefor, each composed of panels hinged together, a vertical rock shaft carrying one of the panels of each door and forming a vertical hinge axis therefor at its outer edge, each of said rock shafts having a crank arm, a channel arranged over each door, said channels being arranged in lines with each 100 other and forming an interrupted guideway over the doorway, means carried by the inner panel of each door, at its upper end, to engage and operate in its associated guideway, a guide shoe located at the interruption 105 of said guideway, and between the proximate ends of said channels to be engaged by the inner panel of each door as it approaches 110
17. The combination of a doorway, a pair of doors therefor, each composed of panels hinged together, a vertical rock shaft carrying one of the panels of each door and forming a vertical hinge axis therefor at its outer edge, each of said rock shafts having a crank arm, a channel arranged over each door, said channels being arranged in lines with each 115 other and forming an interrupted guideway over the doorway, means carried by the inner panel of each door, at its upper end, to engage and operate in its associated guideway, a guide shoe located at the interruption 120 of said guideway, and between the proximate ends of said channels to be engaged by the inner panel of each door as it approaches 125

closed position to cause said guideway engaging means of each door to pass through the interruption of the guideway, and to enter its associated channel, an operating shaft 5 having a control handle and a crank arm, and connections between the operating shaft crank arm, and the crank arms on said rock shafts, whereby said doors are operated in unison.

In testimony whereof I have hereunto set 10 my hand in the presence of the subscribing witnesses, on this 23rd day of April, A. D. 1910.

HAROLD ROWNTREE.
